INKER THROW-OFF

Charles W. Harrold, University Heights, and Alfred Stull Harris, Cleveland Heights, Ohio, assignors to Harris-Seybold-Potter Company, Cleveland, Ohio, a corporation of Delaware

Application February 15, 1937, Serial No. 125,770

18 Claims. (Cl. 101—351)

This invention relates to improvements in inker throw-off mechanism, that is to say mechanism for interrupting the flow of ink to the form of a press when the printing operation is interrupted while the press continues to run. As is well known in the art this tripping of the impression may be accomplished manually by the operator or automatically upon the occurrence of some contingency, such for instance as the failure of a sheet feeder to properly present a sheet to the press.

In inkers of the type described in United States Letters Patent No. 1,980,639, granted to A. Schlesinger, sets of rollers are employed for preliminarily working the ink before the latter is passed on to the other rollers of the inker and finally applied to the form. In such inkers there may be a plurality of sets of such ink working or mixing rollers, and each set may be arranged to work the ink for several cycles of the printing press before passing it along to the other rollers of the inker. Under these conditions a sufficient charge of ink is carried by each set of mixing rollers to supply the form with ink for several impressions. The different sets of mixing rollers come into operative relation, one set at a time, with the form inking rollers. There is then available in the inker beyond the ductor roller a supply of ink equal to the supply being currently used multiplied by the number of sets of mixing rollers. If all of this ink were permitted to be distributed to the form rollers while the press was off impression, obviously the form rollers would be greatly over-supplied with ink, and upon the resumption of printing a number of sheets would receive too great a quantity of ink. It is therefore desirable to provide means for automatically cutting off the flow of ink before it reaches the form rollers. Incidentally it is desirable also when the press trips to cut off the supply of ink to the mixing rollers before opportunity is afforded for either set of those rollers to collect more than one charge of ink.

One of the objects of the invention therefore is the provision of means for avoiding the over-inking of sheets passing through the press upon the resumption of printing following a tripping of the press, where the inker is of the type specified.

Another object is the provision of means for interrupting the transfer of ink from the mixing rollers to the form inking rollers at times when the press is running but is not printing.

A further object of the invention is the provision of means for interrupting the collection of ink by the mixing rollers at the same time sub-

stantially as the transfer of ink to the form inking rollers is interrupted.

Still another object is the provision of manually operated means for restoring normal contact between such ink mixing rollers and the remaining rollers of the inker while the press is still off impression, so that all rollers of the inker may be inked up before any sheets of paper are fed to the press at the beginning of a printing job or run.

Other objects and features of novelty will appear as we proceed with the description of those embodiments of the invention which, for the purposes of the present application, we have illustrated in the accompanying drawings, in which

Fig. 1 is a diagrammatic side elevational view of an offset press with our inker in operative position thereon, the view being taken partly in section directly behind the forward side of the frame of the machine.

Fig. 2 is a similar view showing a modification.

Fig. 3 is a diagrammatic view on a larger scale showing a portion of the mechanism of Fig. 1, the frame of the machine being removed and the mixing rollers being shifted to their other operative position.

Fig. 4 is an end elevational view, partly broken away, showing the driving mechanism for operation of the cams controlling the movements of the ductor roller and the shifting of the mixing rollers from one position to the other.

Figs. 5 and 6 are diagrammatic side elevational views of a modification of the invention in which the ink mixing rollers may be held entirely out of contact with the other rollers of the inker, Fig. 5 showing such out of contact position and Fig. 6 showing one of the operative positions, the forward side of the frame being removed in each case.

Fig. 7 is a side elevational view on a larger scale of a portion of the inker of Fig. 1, the form rollers being raised out of contact with the plate cylinder of the press.

Fig. 8 is a detail view on a larger scale showing certain driving mechanism employed in connection with the invention, as illustrated in Fig. 1, and showing a transfer roller in operative position for conveying ink from the receiving roller to the ink drum.

Fig. 9 is a fragmental view showing the transfer roller of Fig. 8 in position to interrupt the flow of ink from the receiving roller to the ink drum.

Fig. 10 is a plan view of certain connections in the throw-off control, and

Fig. 11 is an elevational view of the same, partly in section on the line 11—11 of Fig. 10. For the purpose of illustrating a suitable application of the invention we have indicated in the drawings the principal parts of a printing press of the offset type, including an impression cylinder 10, a blanket cylinder 11, and a plate cylinder 12, the cylindrical printing surface of the latter being hereinafter referred to as the form of the press.

For the purposes of the present application the cylinders 10 and 12 may be understood to be mounted on fixed axes. The blanket cylinder 11 however is mounted to turn around the axis of a shaft 14 which is supported eccentrically in cylindrical blocks 15 mounted to have a slight turning movement in the frame of the press. One of these blocks 15 carries a lug 16 to which is pivoted a link or rod 17 forming a part of the trip mechanism of the press. Movement in the direction of the arrow in Fig. 1 communicated to the link 17 by the trip mechanism is transmitted also to the corresponding block at the other end of shaft 14, causing the axis of the shaft to move diagonally downward toward the left, shifting the cylinder from printing position indicated by circle A in Fig. 1 to off position indicated by circle B in that figure. Trip mechanism of this character is more fully illustrated and described in application for United States Letters Patent Serial No. 756,794, filed December 10, 1934, by Charles W. Harrold and Clyde G. Horton.

In that form of the invention illustrated in Figs. 1, 3, 4 and 7 to 11 inclusive the inker comprises a suitable frame, indicated at 18, in which there is supported an ink fountain 19. A fountain roller 21 supported on a shaft 20 is so arranged as to take ink from fountain 19. At regular intervals a doctor roller 22 moves into surface contact with fountain roller 21 to receive a charge of ink therefrom, after which roller 22 returns to ink delivering position shown in Figs. 1 and 3. For this purpose the roller 22 is journaled in a pair of arms 23 which are mounted to swing with an oscillatable shaft 24 journaled in the frame. At one end of this shaft there is keyed an arm 25 having on its outer extremity a follower 26 which runs upon a cam 27 mounted upon shaft 20. This cam has two high spots. Consequently roller 22 will be lifted into contact with roller 21 twice during each revolution of shaft 20. At other times the roller 22 will be held in its lower or ink delivering position by means of a spring 28 surrounding a bolt 29 pivoted at 30 to the frame, this spring acting against a perforated lug 31 which may be conveniently formed integral with arm 25. The bolt 29 extends through the perforation in lug 31 and carries a pair of nuts 32 forming an adjustable stop by means of which the ink delivering position of the roller may be adjusted with nicety.

Somewhat below the delivery position of roller 22 there is a shaft 33 journaled in the side members of the inker frame. Upon this shaft between the side members of the inker frame there is fixed a frame comprising two end plates 34 in which are rotatably mounted four shafts 35, 35', 36 and 36'. These shafts carry ink working or mixing rollers 37, 37', 38 and 38'. The rollers 37 and 37' form one set and the rollers 38 and 38' form another set. Below shaft 33 there is a shaft 39 upon which is mounted an ink receiving roller 40. The frame which carries the mixing rollers has two operative positions, one shown in Fig. 1 where the roller 37 contacts with the doctor

roller 22 when the latter is in its ink delivering position, and where the roller 38' contacts with the ink receiving roller 40. The other position is shown in Fig. 3, where the roller 38 contacts the doctor roller and the roller 37' contacts the ink receiving roller. With these rollers in the first position the set 37, 37' is receiving ink from the doctor roller and mixing it, the other set in the meantime further mixing the ink upon the surfaces of its rollers and delivering it to the receiving roller 40. In the other operative position these functions are interchanged, that is the set 38, 38' is receiving ink from the doctor roller while the set 37, 37' is delivering ink to the receiving roller. In order that the frame for the mixing rollers may be shifted periodically from one operative position to the other, an arm 41 is keyed to shaft 33 at one end thereof, and a roller 42 on the extremity of this arm rides upon a cam 43 pinned to shaft 20. The arm 41 is urged toward the left and maintained in contact with its cam 43 by means of a spring 44 which is attached at one end to the arm and at the other end to any convenient anchorage on the frame of the inker.

A series of form rollers 45, 46, 47 and 48 are arranged to engage the form on cylinder 12. The form rollers contact storage rollers 49 and 50, and the latter rollers receive ink through intermediate rollers 51 and 52 from an ink drum 53. Ink is fed to the drum 53 from a transfer roller 54 which is also in contact normally with receiving roller 40.

Preferably the form rollers and associated parts are so mounted as to be capable of being raised out of contact with the cylinder 12 conveniently and quickly. To this end pairs of arms 55 and 56 are rotatably mounted upon the shaft 57 of drum 53. All of the rollers 45, 46, 49 and 51 are journaled in the arms 55 or projections thereof, and similarly the rollers 47, 48, 50 and 52 are carried by the arms 56. When the arms 55 and 56 are swung upwardly and outwardly the rollers 45, 46, 47 and 48 are caused to clear the cylinder 12, as shown in Fig. 7.

The means for accomplishing this raising of the form rollers comprises on each side of the press a pair of toggle links 58 pivoted at their outer ends to the arms 55 and 56 and at their inner ends to an upright link 59, the latter being connected pivotally to a lever 60 which is pivotally mounted at 61 on the frame of the inker. From the opposite end of this lever a rod 62 extends downwardly to a lip 63 which is attached to the block 15. When the rod 62 is pulled downwardly upon the tripping of the press the link 59 of course moves upwardly, spreading the toggle links 58 and raising the arms 55 and 56. The upward movement of the link 59 is limited by a stop 64 on the frame.

In order to break connection between the receiving roller 40 and the drum 53 for the purpose of interrupting the transfer of ink from the upper part of the inker to the form rollers, the transfer roller 54 is mounted to swing away from ink receiving roller 40. Roller 54 is supported at its ends in brackets 65 which are mounted to oscillate upon sleeves 65a, carried on studs 66 fixed in the frame. These brackets are provided with slots 67 which receive the studs, and set screws 68 by means of which the engagement of the roller 54 with the drum 53 may be adjusted. An extension 69 on each of the brackets 65 is pivotally connected with a sleeve 70 surrounding an eye-bolt 71, each of these sleeves being ad-

justable lengthwise of its bolt by means of nuts 72 and 73. The bolts 71 are pivotally connected with short cranks 74 that are keyed to a rock shaft 75 journaled in the frame. Shaft 75 carries another crank 76 (Fig. 1) connected with a rod 77 by means of which the shaft is oscillated. When rod 77 is pulled to the left the extensions 69 on brackets 65 are raised, as indicated in Fig. 9, and the roller 54 is swung away from contact with roller 40. When the rod 77 is moved again to the right the parts take the positions indicated in Fig. 8, which is the normal operating condition of the inker. At this time the pivotal connections between the shaft 75 and the extension 69 come into line so as to more readily hold the roller 54 in its operative position.

As shown in Fig. 10 the opposite end of rod 77 is turned at a right angle and pivotally connected with a crank 78 that is rotatably mounted upon a stud 79 which is threaded into the frame. The crank 78 is made integral with an arm 80 which is grooved to form a slide guide for a bar 81. The latter has a slot 82 therethrough which takes a stud 83 that is threaded into the arm 80. A coil spring 84 between the head of the stud and the bar 81 tends to hold the latter against accidental movement. The forward end of bar 81 has a slot 85 therein which is adapted to receive a pin 86 in another crank 87, the hub of which is rotatably mounted on stud 79. When the bar 81 is in the position illustrated in Figs. 10 and 11 the two cranks 87 and 76 are locked together by the intermediacy of pin 86 engaging slot 85 in bar 81. When bar 81 is pulled to the rear far enough to disengage slot 85 from pin 86 the two cranks 78 and 87 are free to move relatively to each other.

As previously stated, when the press is tripped the roller 54 is swung away from engagement with roller 40 by the movement of rod 77 toward the left. In order to accomplish this the crank 87 must be drawn downwardly. In the form of the invention illustrated in Fig. 1 a short rod 88, pivotally connected with crank 87, is connected to a lever 89 which is keyed to the outer end of a short shaft 91 extending through one of the inker frames 18. Keyed to the inner end of this shaft is another lever 89' which is connected by a link 90 with one of the arms 55. Hence, when the arm 55 rises, as it does upon the tripping of the press, motion is transmitted to rod 88 in the opposite direction, thereby pulling the crank 87 downwardly.

In the form of the invention illustrated in Fig. 2, where no provision for raising the form rollers is shown, crank 87 is connected directly with lip 63 by a push and pull rod 92.

The drum 53 is appropriately driven from the printing press through a gear 93 on its shaft 57 so as to have a surface speed substantially the same as the surface speed of the press cylinders. The rollers 49 and 50 of the form roller group are preferably driven by gears (not shown) from the drum 53. The other rollers of the form roller group, and roller 54, are preferably driven frictionally. The drive for the rollers of the upper group may be traced by reference to Figs. 1, 4 and 8. Drum 53 has rigid therewith a gear 94 which meshes with a gear 95 that turns freely upon shaft 39 of ink receiving roller 40. Gear 95 meshes with a gear 96 that rotates freely on shaft 33 and in turn meshes with gears 97 and 98, the latter gears being fixed with respect to rollers 37 and 38. Roller 40 is driven by friction from roller 54 and also at times from rollers

37' and 38'. Rollers 37 and 38 however are driven positively by the gears 95, 96, 97 and 98. Rollers 37' and 38' may also be driven positively if desired, but we prefer to drive them frictionally by contact with rollers 37 and 39 respectively.

The drive for shaft 20 upon which is mounted the fountain roller comes from shaft 51. On the latter shaft outside of the frame there is a pinion 99 which meshes with a large gear 100 mounted to turn freely on shaft 39, see Fig. 4. On the same hub with gear 100 is a pinion 101 which meshes with a gear 102 turning freely on shaft 33. A sprocket wheel 103 is formed integral with gear 102 and serves to drive a chain 104 which runs over a sprocket wheel 105. The latter sprocket is fixed to a short shaft 20' mounted in the frame member 18 in axial alignment with shaft 20, to which it is adapted to be operatively connected by means of a dog clutch comprising the part 106 fixed to shaft 20' and the part 107 slideable on shaft 20 but held from turning thereupon by a key or spline 108.

The reduction of speed effected by the gearing just described is preferably such that shaft 20 turns at a rate approximately one-tenth that of shaft 51. Hence the frame supporting the mixing rollers 37, 37', 38 and 38' is shifted once for every five revolutions of the drum 53. The ductor roller 22 moves up to take ink from the fountain roller 21 twice for every ten revolutions of the cylinder 12, or once for every five revolutions, and the timing is such that the roller 22 returns to ink delivering position at substantially the same time as the shift of the mixing rollers takes place.

It is desirable not only to interrupt the transfer of ink from the rollers of the upper group to the rollers of the lower group each time the press is tripped, but also to interrupt the shifting of the mixing rollers and the oscillations of the ductor roller. In order to do this we stop the rotation of shaft 20 and with it the rotation of cams 27 and 43. This is accomplished by means of a rod 109 connected with the arm 80, previously mentioned, and extending through a nodule pin 110 on a bell crank 111 pivotally mounted on the frame. A collar 112 fixed to the rod is adapted to engage the upper side of the nodule pin and a coil spring 113 bearing against another collar 114 engages the lower side of the nodule pin. When the rod 109 is in its normal raised position the clutch 106, 107 is in engagement. When however the rod 109 is pulled down because of the tripping of the press, collar 112 moves bell crank 111 clockwise, producing a pull upon a link 115 which is pivoted to a shifting yoke 116 pivotally mounted on the frame at 117. By this means the clutch is disengaged and the rotation of shaft 20 and likewise of cams 27 and 43 is interrupted.

In Figs. 5 and 6 we have illustrated a means which may be used either in addition to the clutch control just described or as a substitute therefor. In either case no additional ink can reach the mixing rollers after the press is tripped because the frame upon which those rollers are carried is locked in an intermediate position half-way between the two operative positions, so that the rollers of both sets are clear of engagement not only with the receiving roller 40 but also with the ductor roller 23. In this construction the shaft 33, to which the plates 34 are fastened, has keyed thereto a bracket 118 having a V-notch 119 at its lower end and a pair of upwardly extending spaced lugs 120 at its upper end. An

arm 121 is loosely mounted on the shaft 33. Coil springs 122 interposed between the arm 121 and the lugs 120 tend to hold the arm in a median position with respect to the bracket, as illustrated in Fig. 6, which shows the parts in their normal running position. The arm swings back and forth due to the action of cam 43 and spring 44 which function in the same manner as in the case of arm 41 of Fig. 1. On the frame of the inker at 123 there is pivotally mounted a lever 124 connected at one end to a rod 209 and at the other end carrying a small roller 125 which is adapted to engage the sides of V-notch 119 in the bracket. When the rod 209 is pulled downwardly by means similar to that heretofore described with respect to rod 109 roller 125 rises into engagement with the V-notch and turns the bracket 118 to its intermediate position and holds it there, thus maintaining the two sets of rollers 37, 37' and 38, 38' out of engagement with both of the rollers 22 and 40. In the event that there is no provision for stopping the shaft 20 simultaneously with this action upon bracket 118, the arm 121 will continue to swing back and forth, the springs 122 yielding to permit such action. The condition of these parts when the press has been tripped is illustrated in Fig. 5.

Operation.—Assuming that the press is about to be started for a job of printing, it is desirable to ink up the rollers of the inker and apply a charge of ink to the form on cylinder 12. With the cylinder 11 thrown off, that is in position B of Fig. 1, the operator pulls out bar 81 and starts the press. The form rollers 45, 46, 47 and 48 will then be in the raised position illustrated in Fig. 7, and the crank 87 will be drawn down as shown in that figure. This crank is however disconnected from crank 18, the slide guide 80 and the bar 81, and the latter may be shifted to and held in the normal running position illustrated in Fig. 1. Ink will then be taken from the fountain roller 21 by ductor roller 22 and transferred to first one and then the other of the sets of mixing rollers 37, 37' and 38, 38' and from those sets alternately to the receiving roller 40 and by way of transfer roller 54 to drum 53 and thence down to the rollers of the lower group including the form rollers 45, 46, 47 and 48. This action is permitted to continue until the required charge of ink has been distributed throughout the rollers of the inker. Then the operator by suitable means pulls rod 17 to the left throwing cylinder 11 to printing position A and raising crank 87, after which he pushes bar 81 in to normal position, locking cranks 87 and 18 together. The feed of paper sheets is also begun at the same time, the control of the sheet feeder being usually effected simultaneously with the operation of rod 17. The press is then in full operation.

60 When the press is tripped, either manually or automatically, the roller 54 is immediately swung down away from ink receiving roller 40, and no further ink is delivered to the lower group of rollers. This interruption of the flow of ink to 65 the lower group of rollers is the essential action of our throw-off. However we prefer at the same time to stop the oscillation of the ductor roller and the shifting of the mixing rollers, and in most cases we prefer also to raise the form rollers out 70 of engagement with the form, all as previously explained. The inker then remains in a ready condition suitable for resuming the printing operation without the disadvantage of loss and inconvenience from over-inking sheets. As before 75 stated, this disadvantage is especially important

and therefore especially to be avoided in an inker of the type illustrated where there is present a large quantity of ink in the rollers of the upper group, due to two sets of mixing rollers, each with a supply for several revolutions of the press. 5

Variations from the described structures may be employed. Accordingly we desire it to be understood that the scope of the invention is to be regarded as defined exclusively by the appended claims rather than by the foregoing description 10 or the accompanying illustration. 10

Having thus described our invention, we claim:

1. In combination, an inker comprising a fountain roller, a ductor roller mounted to oscillate between ink receiving and ink delivering positions, an ink receiving roller mounted in fixed bearings, two sets of ink mixing rollers, means for moving one set into contact with the ductor roller and the other set into contact with the receiving roller, and vice versa, a set of rollers for carrying ink from said receiving roller to the form to be inked, and throw-off means for interrupting the transfer of ink from said receiving roller to said last named set of rollers. 15

2. In combination, an inker comprising a ductor roller mounted to oscillate between ink receiving and ink delivering positions, an ink receiving roller, two sets of ink mixing rollers, means for moving one set into contact with the ductor roller and the other set into contact with the receiving roller, and vice versa, a set of rollers for carrying ink from said receiving roller to the form to be inked, throw-off means for interrupting communication between said receiving roller and said last named set of rollers, and means associated with said throw-off means for interrupting the oscillation of said ductor roller. 20

3. In combination, an inker comprising a ductor roller mounted to oscillate between ink receiving and ink delivering positions, an ink receiving roller, two sets of ink mixing rollers, means for moving one set into contact with the ductor roller and the other set into contact with the receiving roller, and vice versa, a set of rollers for carrying ink from said receiving roller to the form to be inked, throw-off means for interrupting communication between said receiving roller and said last named set of rollers, and means associated with said throw-off means for interrupting the bodily movement of said sets of mixing rollers. 35

4. In combination, an inker comprising a ductor roller mounted to oscillate between ink receiving and ink delivering positions, an ink receiving roller, two sets of ink mixing rollers, means for moving one set into contact with the ductor roller and the other set into contact with the receiving roller, and vice versa, a set of rollers for carrying ink from said receiving roller to the form to be inked, and throw-off means arranged to interrupt the bodily movement of said sets of mixing rollers. 40

5. In combination, an inker comprising a ductor roller mounted to oscillate between ink receiving and ink delivering positions, an ink receiving roller, two sets of ink mixing rollers, means for moving one set into contact with the ductor roller and the other set into contact with the receiving roller, and vice versa, a set of rollers for carrying ink from said receiving roller to the form to be inked, and throw-off means for interrupting the oscillation of said ductor roller and the bodily movement of said sets of mixing rollers. 45

6. In combination, an inker comprising a duc- 50

tor roller mounted to oscillate between ink receiving and ink delivering positions, an ink receiving roller, two sets of ink mixing rollers interposed between the ductor roller and the receiving roller, means for moving one set into contact with the ductor roller and the other set into contact with the receiving roller, and vice versa, a set of rollers for carrying ink from said receiving roller to the form to be inked, throw-off means for interrupting communication between said receiving roller and said last named set of rollers, and means associated with said throw-off means for interrupting the oscillation of said ductor roller and the bodily movement of said sets of mixing rollers.

7. In an inker for a printing press, a fountain roller, a ductor roller, form rollers, ink mixing rollers adapted to receive ink from the ductor roller and to mix it during a plurality of cycles of the press, an ink receiving roller, means for producing relative movement between said mixing rollers and said receiving roller to cause said receiving roller to receive ink from the mixing rollers during a plurality of cycles of the press subsequent to the first named cycles, means for taking ink from said receiving roller and advancing it toward said form rollers, and throw-off means for interrupting the transmission of ink from said receiving roller toward said form rollers.

8. In combination, form rollers, ink mixing rollers adapted to receive ink periodically and mix it during a plurality of cycles of the press, an ink receiving roller adapted to receive ink from the mixing rollers during a plurality of cycles of the press subsequent to the first named cycles, means for transferring ink from said ink receiving roller to said form rollers, and throw-off means for separating the form rollers from the form and simultaneously interrupting the transfer of ink from the receiving roller to the form rollers.

9. In an inker for a printing press, form rollers, two sets of ink mixing rollers, means for receiving ink from one set of mixing rollers at a time and transferring it to said form rollers, means for shifting said sets of mixing rollers periodically to cause them to engage alternately with said ink receiving means, and throw-off means for interrupting the transfer of ink to said form rollers and for simultaneously interrupting said shifting means.

10. In an inker for a printing press, form rollers, two sets of ink mixing rollers, a ductor roller for delivering ink alternately to each of said sets, means for receiving and transferring ink from said ink mixing rollers to said form rollers, and throw-off means for interrupting the transfer of ink to said form rollers and for simultaneously interrupting the operation of said ductor roller.

11. In an inker for a printing press, form rollers, two sets of ink mixing rollers, means for receiving ink from one set of mixing rollers at a time and transferring it to said form rollers, cam operated means for shifting both sets of mixing rollers periodically to cause the two sets to engage alternately with said ink receiving means, and throw-off means for interrupting the transfer of ink from said mixing rollers to said form rollers and for simultaneously declutching said cam operated means.

12. In an inker control mechanism for a printing press, an oscillatable member, inker throw-off means adapted to be actuated by the oscillation

of said member, a throw-off operating element adapted to be actuated automatically when the press is tripped, a crank arranged to turn about the same axis as said oscillatable member and connected with said operating element, and means for locking said crank to said oscillatable member, said means when withdrawn from locking position serving as a handle for turning the oscillatable member independently of said crank.

13. In combination, an inker comprising a ductor roller mounted to oscillate between ink receiving and ink delivering positions, an ink receiving roller, an oscillatable frame, two sets of ink mixing rollers mounted on said frame, means for shifting the frame periodically to move one set of mixing rollers into contact with the ductor roller and the other set into contact with the receiving roller, and vice versa, and throw-off means for shifting said frame to an intermediate position with the two sets of mixing rollers out of contact with the ductor roller and the receiving roller.

14. In combination, an inker comprising a ductor roller mounted to oscillate between ink receiving and ink delivering positions, an ink receiving roller, an oscillatable frame, two sets of ink mixing rollers mounted on said frame, means comprising yieldable connections operating to shift the frame periodically to move one set of mixing rollers into contact with the ductor roller and the other set into contact with the receiving roller, and vice versa, and throw-off means for shifting said frame to and holding it in an intermediate position with both sets of mixing rollers out of contact with the ductor roller and the receiving roller, such movements of said first named shifting means as may tend to occur thereafter being absorbed in said yieldable connections.

15. In a printing press having a form carrying cylinder, mechanism for inking the form comprising an ink supply, a group of form inking rollers, ink mixing rollers between the supply and the form inking group adapted to receive a charge of ink from the supply and work it independently of the form inking group during more than one revolution of the cylinder, and means to cause the mixing rollers to intermittently transfer ink to the form inking group for transmission to the form, and throw-off means operable upon discontinuance of the printing operation to render said last mentioned means inoperative.

16. In a printing press having a form carrying cylinder, mechanism for inking the form comprising an ink supply, a group of form inking rollers, a plurality of sets of ink mixing rollers between the supply and the form inking group, each set of mixing rollers being adapted to receive a charge of ink from the supply and work it independently of the form inking group during more than one revolution of the cylinder, and means for causing each set of mixing rollers, one set at a time, to transfer ink to the form inking group for transmission to the form, and throw-off means operable upon discontinuance of the printing operation to render said last mentioned means inoperative.

17. In an inker for a printing press, an ink supply, form rollers, ink mixing rollers adapted to receive a charge of ink from the supply and to isolate it and mix it during a plurality of cycles of the printing press, ink transmitting rollers interposed between the mixing rollers and the form rollers, said mixing rollers and transmitting rollers being arranged and operated to cause

transfer of a charge of ink from the former to the latter, and throw-off means for interrupting the transfer of ink from the mixing rollers to the transmitting rollers.

5 18. In an inker for a printing press, an ink supply, form rollers, a plurality of sets of ink mixing rollers, each set being adapted to receive ink from the supply and mix it during a plurality of cycles of the press, ink transmitting

rollers interposed between the mixing rollers and the form rollers, said mixing rollers and transmitting rollers being arranged and operated to cause each set of mixing rollers periodically to transfer ink to the ink transmitting rollers, and throw-off means interrupting the periodic transfer of ink to the transmitting rollers. 5
